his ATTORNEY

UNITED STATES PATENT OFFICE

WILLIAM M. SCOTT, OF TREDYFFRIN TOWNSHIP, CHESTER COUNTY, PENNSYLVANIA,
ASSIGNOR TO I-T-E CIRCUIT BREAKER COMPANY, OF PHILADELPHIA, PENNSYLVANIA, A CORPORATION OF NEW JERSEY

SWITCH APPARATUS

Original application filed April 12, 1929, Serial No. 354,480. Divided and this application filed April 5, 1930, Serial No. 441,759. Renewed November 17, 1931.

My invention relates to electrical switch apparatus and more particularly to automatic switch apparatus of the electromagnetic type.

5 My invention resides in switch apparatus comprising electromagnetic arc-extinguishing or blow-out structure wherein blow-out coils disposed on opposite sides of switch contacts are each housed within an insulating 55 enclosing structure of arc-resisting material comprising a member detachable with respect to the switch mounting structure; and more particularly, the said enclosing structure 60 comprises a partition or wall member of insulating material formed substantially integral, as by molding, with the switch mounting panel, or base, and a cup-like member or cover detachable with respect to said base and forming with said partition or wall an enclosure 65 for a blow-out coil.

My invention further resides in apparatus of the character hereinafter described and claimed.

25 For an understanding of my invention, reference is had to the accompanying drawings, in which:

Fig. 1 is a side elevational view of switch apparatus constructed in accordance with my 30 invention;

Fig. 2 is an elevational view of one of the parts;

Fig. 3 is an end elevational view, looking 35 toward the left in Fig. 2;

Fig. 4 is a sectional view, the section taken on the line 4—4 in Fig. 2;

Fig. 5 is a front elevational view of a pair 40 of magnetic blow-out coils;

Fig. 6 is a side elevational view, looking 45 toward the left in Fig. 5;

Fig. 7 is a front elevational view partly broken away, looking toward the left in Fig. 1;

Fig. 8 is a fragmentary view taken from 50 Fig. 7, some of the parts removed; and

Fig. 9 is a plan view partly in section the section taken on line 9—9 in Fig. 8.

Referring to Figs. 1 and 7, a base or panel 1 of suitable insulating material, is provided 55 with barriers 1a extending transversely thereto and has mounted thereon electrical

switch apparatus comprising a stationary contact 2 suitably secured to the base, as by a conducting stud 3 which comprises a lead conductor of the circuit to be protected, and a movable contact 4 mounted upon a transversely extending bar or support 5, and electrically connected by a flexible conducting strip 6 to a terminal 7 on the bracket 8 secured to base 1. Terminal 7 is connected to one end of an overload coil 9 whose other 60 end is connected to the conducting stud 10 comprising the other lead from the circuit to be protected.

Cooperating with movable contact 4, and mounted also upon the switch arm support 5 65 is an auxiliary or arcing contact 11 carried on the end of a resilient conducting arm 12. In the closed position of the switch, contact 11 is in engagement with a contact 13 suitably secured to the base, as by screw 13a, which 70 is positioned and spaced with respect to contact 2 by a raised portion or boss 13b forming a part of the base. Means for extinguishing the arc between contacts 11 and 13, referring more particularly to Figs. 5 and 6, comprises 75 a pair of blow-out coils 14 and 15 arranged on each side of the contacts in the usual manner, and having their inner ends connected to each other by a conducting strip or bridge 16, and their outer ends connected together by 80 a conducting strip 17 having a rectangular opening 18 therein for a purpose hereinafter described. Conducting strip 16 is suitably secured to the base by contact 13 and is in electrical contact therewith. The conducting strip 17 is likewise clamped to the base by contact 2, the extension of which passes through aperture 18, thereby connecting coils 85 14 and 15 in parallel between contacts 2 and 13.

Insulating enclosing structure for the blow-out coils, referring more particularly to Figs. 2, 3, 4, 8 and 9, comprises partitions or walls 19 preferably integrally mounted to the base or panel 1 as by moulding, and of substantially the same material, and cover members 20 of arc-resisting material detachably secured with respect to the base and partitions. As viewed in Figs. 8 and 9, an individual pair of blow-out coils are disposed adjacent 90 95 100

- the opposing faces of two partitions or walls and are suitably housed by the cup-like covers 20 which form with partitions 19 receptacles for completely enclosing the blow-out coils. 5 Except for the end walls, the members 19 form common wall structure for a pair of unrelated coils. Each partition or wall 19, as previously mentioned, is preferably moulded to base 1, forming an integral part therewith, and is generally of insulating material of inferior arc-resisting characteristics to that used in the cover members 20. Accordingly, the cover members are so designed that they alone are subjected to the intense heat 10 of the arc. To this end, the cover members 20 are each provided with offset portions 21, Figs. 3 and 4, adapted to abut each other when the covers are in position to shield and protect an appropriate portion of base 1 not 15 shielded by the contact 13, and to furthermore space the cover members from each other to provide suitable clearance for the movable contact element between the same. The interior of each cover member 20 is provided with a shoulder 22 extending along three sides of the same for engaging the corresponding edges of a partition 19 to relatively position the same. The edges of the cover abutting base 1 seat within a correspondingly 20 shaped depression 20a in the base 1 and have a pair of notches 23 and 24 therein for receiving the bridging conductors 16 and 17 respectively of the blow-out coils. The front side of the cover partially overlying the outer edge of the partition is provided with a semi-circular notch 25 and a longitudinally extending recess 26 for receiving a holding screw 27 and a clamp 28. Screw 27 is secured, as by an insert 27a, to the front edge 25 of partition 19 and serves to clamp the front edge of cover 20 to the partition. As viewed in Fig. 9, two of the partitions 19, when three pairs of blow-out coils are employed, have a cover member mounted on each side thereof 40 and clamped thereto by common clamping structure 27 and 28. Accordingly, quick and easy access to the blow-out coils may be accomplished by simply unloosening screw 27 and clamp 28.
- 45 50 In the opening movement of the circuit breaker, the main movable contact member 4 is first withdrawn from the fixed contact 2; while for the instant, movable contact 11 maintains its engagement with fixed contact 13, thus bringing the blow-out coils into series with the main circuit and thereby rendering them effective to rupture the arc drawn in the space between them incident upon the further opening of the switch and 55 consequent withdrawal of contact 11 from engagement with contact 13.
- In order to prevent arcing at the main contacts of the circuit breaker, it is essential that the impedance of the blow-out coils shall 60 be a minimum consistent with the desired magnetic effect. High blow-out efficiency is attained by disposing the two coils on opposite sides of the arcing chamber, the effectiveness thus secured being such that iron may be altogether omitted from the magnetic circuit and coils of relatively few turns are found to suffice. The cover members 20 which shield the blow-out coils, the partition members 19, and the base area above the contact 13, are of material having high arc-resisting characteristics; accordingly, base 1 and partitions 19, being effectively shielded from arcing, the material from which these are moulded may be selected with reference to its insulating qualities rather than for its 70 75 80 ability to resist arcing.
- This application is a division of my co-pending application, Serial No. 354,480, filed April 12, 1929.
- The invention claimed is:
1. Switch apparatus comprising a plurality of sets of coacting stationary and movable contacts, pairs of blow-out coils between which said sets of contacts are respectively disposed, enclosing structure for coils related to different sets of contacts, and a partition member between the coils in said structure and whose plane is substantially parallel to the plane of movement of the movable contacts, said enclosing structure comprising a 85 cover member detachably mounted with respect to said partition member.
  2. Switch apparatus comprising a stationary contact, a movable contact coating therewith, a pair of blow-out coils between which 100 said contacts are disposed, an enclosing structure for each of said coils comprising a wall member of insulating material whose plane is substantially parallel to the plane of movement of the movable contact and a cover member fitted to said wall member.
  3. In switch apparatus, a base member provided with a wall-like portion extending laterally outwardly therefrom, a cover member complementary to said base member and said portion thereof and fitted to the same to provide therewith a chamber, and a blow-out coil disposed in said chamber.
  4. In switch apparatus, a base member provided with a wall-like portion extending laterally outwardly therefrom, a cover member complementary to said base member and said portion thereof and fitted to the same to provide therewith a chamber, means detachably holding said cover member in assembled relation with respect to said base member and said portion thereof, and a blow-out coil disposed in said chamber.
  5. In switch apparatus, a base member provided with a wall-like portion extending laterally outwardly therefrom, a cover member complementary to said base member and said portion thereof and fitted to the same to provide therewith a chamber, means detachably holding said cover member in assembled relation with respect to said base member and said portion thereof, and a blow-out coil 120 125 130 disposed in said chamber.

tion with respect to said base member and said portion thereof, and a blow-out coil disposed in said chamber, said holding means comprising a screw threaded into said portion.

6. In switch apparatus, a base member provided with spaced wall-like portions extending laterally outwardly therefrom, cover members complementary respectively to said portions and the base member and fitted to the latter and the respective associated wall portions thereof to provide with the same chambers, a switch contact fixed to said base member and disposed intermediate said cover

10 members, a second switch contact supported for movement between said cover members into and out of contacting relation with said fixed contact, blow-out coils disposed respectively in said chambers, and means electrically connecting the respective ends of said coils.

7. In switch apparatus, a base member provided with a wall-like portion extending laterally outwardly therefrom, cover members 25 reversed with respect to each other and disposed on opposite sides of said portion and providing therewith chambers, means detachably holding said cover members in assembled relation with respect to said portion, and blow-out coils disposed respectively in said chambers.

8. In switch apparatus, a base member provided with a wall-like portion extending laterally outwardly therefrom, cover members 35 reversed with respect to each other and disposed on opposite sides of said portion and providing therewith chambers, means engaging said portion and common with respect to said cover members and operating to hold 40 the latter in assembled relation with respect to said portion, and blow-out coils disposed respectively in said chambers.

9. In switch apparatus, a base member provided with a wall-like portion extending 45 laterally outwardly therefrom, cover members reversed with respect to each other and disposed on opposite sides of said portion and providing therewith chambers, a clamping element common with respect to said 50 cover members and engaging adjacent edge portions of the latter to clamp the same in assembled relation with respect to said wall portion, and a screw extending through said element and screwed into said wall portion.

55 10. In switch apparatus, a base member provided with spaced wall-like portions extending laterally outwardly therefrom, cover members complementary respectively to said portions and the base member and fitted to the latter and the respective associated wall portions thereof to provide with the same chambers, complementary switch contacts disposed intermediate said cover members, and blow-out coils disposed in said chambers and jointly effective to cause blowing-

out of arcs occurring upon disengagement of said contacts, said cover members provided with complementary abutting portions providing a protective shield for said base member from such arcs.

70

11. Structure for controlling an arc comprising, barrier structure of insulating material, a wall element, of different material having high arc-resisting characteristics, disposed between the region in which the arc is drawn and said barrier structure, and magnetic blow-out structure disposed between said barrier structure and said wall element.

75

12. Structure for controlling an arc comprising, barrier structure of insulating material, a wall element, of different material having high arc-resisting characteristics, disposed between the region in which the arc is drawn and said barrier structure, magnetic blow-out structure disposed between said barrier structure and said wall element, and means for detachably securing said wall element to said barrier structure.

80

13. Structure for controlling an arc comprising, barrier structure of insulating material, a wall element, of different material having high arc-resisting characteristics, disposed between the region in which the arc is drawn and said barrier structure, magnetic blow-out structure disposed between said barrier structure and said wall element, and means shielded from the arc for detachably securing said wall element to said barrier structure.

85

14. Structure for controlling an arc comprising, barrier structure of insulating material, a wall element, of different material having high arc-resisting characteristics, disposed between the region in which the arc is drawn and said barrier structure, an ironless core blow-out coil disposed between said barrier and said wall element, and means shielded from said arc by said wall element for detachably securing said wall element to said barrier structure.

90

15. A circuit breaker comprising a base, fixed contact structure mounted on the front thereof, contact structure movable toward and away from said base into and out of engagement with said fixed contact structure, magnetic blow-out elements extending normal to said base on opposite sides of the path of said movable contact structure, individual encasing members for said blow-out elements of arc-resistant material and removable forwardly from said base and independently of displacement of said fixed contact structure, and means for releasably holding said encasing members accessible from the front of said base.

95

16. A circuit breaker comprising a base, fixed contact structure mounted on the front thereof, contact structure movable toward

100

105

110

115

120

125

130

and away from said base into and out of contact with said fixed contact structure, iron-less core blow-out coils having their axes parallel to said base and intercepting the path of movement of said movable contact structure, individual encasing members for said blow-out coils of arc-resistant material and removable forwardly from said base independently of displacement of said fixed contact structure, and means for releasably holding said encasing members accessible from the front of said base.
